UNITED STATES PATENT OFFICE.

SETH J. NORTH AND BRYCE W. McCCLYMONT, OF DETROIT, MICHIGAN.

OIL HEATER.

Application filed June 27, 1923. Serial No. 647,990.

To all whom it may concern:

Be it known that we, SETH J. NORTH and BRYCE W. McCCLYMONT, citizens of the United States, residing at Detroit, county of Wayne, State of Michigan, have invented a certain new and useful Improvement in Oil Heaters, and declare the following to be a full, clear, and exact description of the same, such as will enable others skilled in the art to which it pertains to make and use the same, reference being had to the accompanying drawings, which form a part of this specification.

This invention relates to oil heaters and the object of the invention is to provide a heater which will produce several times the heat of the ordinary type of oil heater. Another object of the invention is to provide a means for preventing the heat from being communicated to the oil tank. A further object of the invention is to provide a pressure feed oil heater in which the pressure in the tank is at all times indicated on a pressure gage provided therefor. Another object of the invention is to provide an oil burner and tank which may be inserted in an oil heater to replace the usual wick type of burner and tank and which has several times the heating capacity of the wick type heater. Another object of the invention is to provide a means for accurately adjusting the quantity of oil flow from the tank to the burner. These objects and the several novel features of the invention are hereinafter more fully described and claimed and the preferred form of construction by which these objects are attained is shown in the accompanying drawings in which—

Fig. 1 is an elevation of an oil heater embodying our invention.

Fig. 2 is a section taken on line 2—2 of Fig. 1.

Fig. 3 is a section taken on line 3—3 of Fig. 2.

Fig. 4 is a section taken on line 4—4 of Fig. 2.

As shown in Fig. 1 the heater comprises a base 1 having legs 2 formed integrally therewith. The base 1 is provided with a cylindrical portion 3 having a notch 4 formed in one side thereof. As shown in Figs. 2 and 3 a series of three brackets 5 are spot welded or otherwise secured in place on the interior of the cylindrical portion 3 and an oil tank 6 is provided having a horizontal flange 7 which is adapted to rest on the upper ends of the brackets 5 and support the tank 6 in position. A plug 8 is threaded into the upper end of the tank 6 as shown in Fig. 1 and may be removed for filling the tank with oil. A nut 9 is supported in the side of the tank 6 having a central aperture into which a tube 10 extends, the said tube terminating near the upper end of the tank above the level of the filler plug 8 as shown in Fig. 2. A member 11 is threaded into the nut 9 on the exterior of the tank and secures the end of the tube 10 in place in the nut as shown. This member 11 is provided with an aperture 12 therethrough which is in communication with an aperture 13 leading to the pressure gage 14 shown in Figs. 1, 2 and 4. The member 11 is also provided with a threaded boss 15 on one side thereof as shown in Fig. 4 and is provided with an aperture 16 therethrough which is normally closed off from the apertures 12 and 13 by the needle valve 17. This needle valve 17 is provided with a threaded portion 18 threaded into the end of the member 11 and is provided with a handle 19 for threading the same into or out of the member 11. A nut 20 is also supported in the side of the tank 6 having a central aperture to receive the end of a tube 21 which terminates adjacent the bottom of the tank 6. A member 22 is threaded into the nut 20 and secures the tube 21 in place and is provided with an aperture 23 therethrough in communication with the tube 21 and with an aperture 24 at right angles to the aperture 23 in communication with a tube 25. A needle valve 26 is threaded into the member 22 and is provided with a bent end 27 for turning the same to open or close the passage provided by the apertures 23 and 24 and thus accurately regulate the oil flow to the burner. A threaded stud 28 extends from the top of the tank 6 and an asbestos washer 29 is positioned over the stud 28 and an apertured sheet metal disc 30 is positioned on top of the asbestos washer 29 and over the stud 28. A metal priming cup 31 is threaded onto the upper end of the stud 28 and bindingly secures the disc 30 and washer 29 in position on top of the tank. The priming cup 31 is provided with a central recess over the stud 28 adapted to receive the stem 32 of an oil burner 33 to which the tube 25 is connected as shown in Fig. 2. This burner is of the pressure type in which the oil is preheated and atomized in order to produce a gas which is ignited in the channel 34 of the burner.

The heater is provided as shown in Figs. 1 and 2 with a cylindrical sheet metal heating drum 35 having a downwardly flared flange 36 which is hinged to the base portion 5 3 at 37 shown in Fig. 1. The portion 3 opposite the hinge 37 is provided with a metal catch 38 which extends through an aperture provided in the flange 36 and secures the upper portion of the heater to the base and 10 the cylindrical portion 35 is provided with a handle 39 pivotally secured thereto by which the heater may be carried.

In operation the tank 6 is filled with oil by removing the filler plug 8 and when the 15 filler plug is replaced a pump is connected to the threaded end 15 of the member 11. By rotating the handle 19 at this time the needle valve 17 is withdrawn so that the aperture 16 is in communication with the 20 apertures 12 and 13 of the member 11. By operation of the pump a pressure is placed on the oil through the aperture 12 and tube 10 and this pressure is indicated by the 25 pressure gage 14. When the correct pressure has been reached the needle valve 17 is again seated as shown in Fig. 4 which closes off the aperture 16 and the pump may be disconnected at this time if desired without loss of pressure. When the needle valve is 30 seated as shown the pressure is communicated to the gage through the tube 10 and apertures 12 and 13 so that the pressure in the tank is indicated at all times by the 35 pressure gage. At this time by depressing the catch 38 shown in Fig. 1 the portion 35 may be turned back on the hinge 37 and the priming cup 31 is filled with gasoline or alcohol which is ignited to preheat the burner. The needle valve 26 is then opened 40 to allow flow of oil by pressure through the tube 21, channels 23 and 24 and tube 25 into the chamber 40 of the burner, shown in Fig. 2, from which it is sprayed through the nozzle 41 and aperture 42 into the chamber 45 43 and passes outwardly through the apertured flange 44 as a gas and is ignited in the channel 34 of the burner. When the heater is in the closed position shown in Fig. 2 the cylindrical portion 35 fits over the burner 50 and disc 30 which acts as a shield and encloses the burner in the upper part of the heater and prevents the heat from traveling downward about the tank 6 and the asbestos washer 29 prevents the heat of the shield 55 and priming cup from being directly communicated to the tank. If desired the edge of the disc 30 may be bent downwardly as shown in dotted lines in Fig. 1 to allow a greater air current to pass upwardly to the 60 burner and at the same time provide a shield for the tank. By adjusting the handle 27 the needle valve 26 may be adjusted to vary the flow of oil to the burner to give greater or less heat as desired. Due to the construction the tank and burner may be easily lifted 65

out of the heater casing to allow the tank to be filled and as most oil heaters are provided with a slot 4 shown in Fig. 1 by removing the wick type burner and tank the pressure type burner and tank may be inserted in the 70 same place. By providing the space 47 between the periphery of the shield 30 and the edge of the heating drum 35 and the space 45 between the flange 7 of the oil tank and the cylindrical base 3 air may pass upwardly 75 from beneath the heater about the oil tank and upon striking the inwardly flared flange 36 the air is thrown inwardly over the top of the oil tank to cool it and passes upwardly through the space 47 about the shield 30 into the heating drum 35 where it is heated and passes out through the apertures 46 in the top of the heating drum. With this construction the oil tank is cooled and the 80 shield 30 prevents the heat from travelling 85 downwardly to the tank.

From the foregoing description it becomes evident that the device is very simple and efficient in operation, will not easily get out of order, is composed of few parts and is of consequent low manufacturing cost and provides a device which accomplishes the objects described. 90

Having thus fully described our invention, its utility and mode of operation, what we claim and desire to secure by Letters Patent of the United States is—

1. An oil heater comprising a hollow base, an oil tank removably supported in the base and provided with a sealed top, an oil burner secured above the tank in spaced relation therewith, a shield secured beneath the burner in spaced relation with the top of the tank, an oil conduit connected to the burner and opening into the bottom of the tank allowing flow of oil under pressure to the burner, means for regulating the flow of oil through the oil conduit, means for indicating the pressure in the tank, and a sheet metal drum secured to the base and fitting about the shield in spaced relation with the periphery thereof. 100

2. An oil heater comprising a hollow base, an oil tank removably supported in the base, a burner secured above the tank in spaced relation therewith, a sheet metal shield secured beneath the burner in spaced relation with the tank, an oil conduit connected to the burner and opening into the bottom of the tank, the tank being adapted for the application of pressure to the surface of the oil, and a sheet metal drum hinged to the base and fitting about the shield in spaced relation with the periphery thereof when in the closed position, the drum and shield forming an enclosure for the burner. 110

3. An oil heater comprising a hollow base, an oil tank removably supported in the base, a sheet metal shield secured to the tank in spaced relation with the upper surface there- 120 125 130

of, an oil burner mounted on the top of the shield, an oil conduit opening from the bottom of the tank and connected to the burner, means for delivering compressed air into the tank above the oil, and a sheet metal drum hinged to the base and enclosing the burner and shield.

4. An oil heater comprising a hollow base, an oil tank removably supported in the base, 10 a circular shield secured to the top of the tank and spaced from the upper surface thereof, an asbestos packing between the top of the tank and the shield, an oil burner mounted above the shield and connected to the tank to allow flow of oil under pressure to the burner, and a cylindrical heating drum forming a cover for the oil burner and fitting about the shield.

5. An oil heater comprising a hollow base, 20 an oil tank mounted in the base, an oil burner mounted on top of the oil tank, a shield between the oil burner and tank, a heat resistant washer spacing the shield from the tank, and a sheet metal cylindrical

drum fitting about the shield at the bottom 25 and forming a cover for the burner.

6. An oil heater comprising a hollow base, an oil tank mounted therein, an oil burner mounted on top of the oil tank, a circular shield between the oil burner and tank, and 30 a cylindrical sheet metal heating drum hinged to the base and forming a cover for the burner, the said cylindrical drum being in spaced relation with the periphery of the shield when in the closed position. 35

7. An oil heater comprising a hollow base, an oil tank removably supported in the base, an oil burner mounted on the top of the oil tank, a sheet metal heating drum hinged to the base and forming a cover for the burner, 40 and a shield secured between the oil burner and tank and extending into the heating drum when in the closed position.

In testimony whereof we sign this specification.

SETH J. NORTH,
BRYCE W. McCORMONT.
